UNITED STATES PATENT OFFICE.

WILEY P. MANGUM, OF SHERMAN, TEXAS.

FIRE-TONGS.

SPECIFICATION forming part of Letters Patent No. 245,849, dated August 16, 1881.

Application filed June 10, 1881. (No model.)

To all whom it may concern:

Be it known that I, WILEY P. MANGUM, a citizen of the United States, residing at Sherman, in the county of Grayson and State of Texas, have invented certain new and useful Improvements in Domestic Fire-Tongs; and I do hereby declare the following to be a full, clear, and exact description of the invention, such as will enable others skilled in the art to 10 which it appertains to make and use the same, reference being had to the accompanying drawings, and to letters or figures of reference marked thereon, which form a part of this specification.

15 My invention relates to an improvement in devices for preventing the legs of fire-tongs from twisting or crossing, and will first be described, and then designated in the claim.

In the drawings hereto annexed, Figure 1 20 is a view of a pair of tongs having my guide device attached, the legs of the tongs being shown closed together. Fig. 2 is a view of the same, but showing the legs of the tongs spread apart. Fig. 3 is a top or edge view of the 25 device. Fig. 4 is a perspective end view of the slot-piece. Fig. 5 is a transverse side view of a leg with the slot-piece.

The letter A designates the handle of an ordinary pair of tongs; B, one of the legs, which 30 is immovable with respect to the handle; and B' the movable leg, jointed at c.

A guide, which I designate the "wing," consists of a metal plate, D, shown as having a segment-shaped or curved form, though, as operated by the construction hereinafter described, it may be straight. I prefer to make the wing rather wide—say, as a maximum, one inch—as when broad it serves its purpose better. This wing is so constructed as to be readily attached to any pair of tongs, old or new, which is a desideratum. This is effected by bending one end around a mandrel to form an eye, e, which will fit about a leg of an ordinary pair of tongs. This eye is left open and the 45 extremity of the bent end f laps over on the wing part, and said extremity is provided with a set-screw, g, which extends through both parts, and by which the open eye may be contracted after it has been placed about the leg, 50 and thus made to tightly clasp the leg. By this construction the wing may be attached, without forging, to any pair of tongs, and its position on the leg may be readily changed so as

to have it higher or lower, as desired, and as indicated in Fig. 1 by broken lines. To the other 55 leg is attached a piece which forms a slot, h, through which the wing passes. The peculiarity of construction of this part enables it also to be attached without forging, and with out at all lessening the strength of the leg. 60

The slotted piece is formed of a continuous metal bar of such shape as to form two eyes or loops, n, each open on one and the same side, and thence extending slightly from the eyes, and the two extended parts connected by the 65 parallel parts p. This bar may be made of wrought-iron forged to the described shape, or of cast-iron and then malleableized, either mode of manufacture admitting of the two parallel parts p being spread apart to open the 70 eyes or loop n and enable the piece to be placed about the movable leg of the tongs and then closed thereon, either tightly or loosely. It will serve its purpose although free to slide up and down on the leg. 75

It will be seen by Fig. 5 the parallel parts p, with the leg, serve to form a slot, h, of proper shape and size to allow the wing to move freely through it.

The end of the wing or guide may be turned 80 or bent a little, as shown at r in Fig. 3, to prevent it from withdrawing from the slot h.

Constructed as herein shown, the device possesses the advantage over others heretofore made of being adapted to be applied readily 85 by an unskilled person to any tongs, whether old or new.

Having described my invention, I claim and desire to secure by Letters Patent of the United States—

A guide device for preventing the legs of fire-tongs from crossing, consisting of a wing-plate, D, having at one end an open eye, e, to fit about one leg of the tongs, and attached thereto, substantially as described, and a slot-piece 95 having open eyes n to fit about the other leg, and a straight part, p, attached to the said eyes and forming the slot through which the wing may move freely, as set forth. 90

In testimony whereof I affix my signature in 100 presence of two witnesses.

W. P. MANGUM.
